for the Inventor

United States Patent Office.

JEREMIAH A. MARDEN, OF BOSTON, ASSIGNOR TO CHARLES E. AND JOHN H. ABBOTT, OF MALDEN, MASSACHUSETTS.

Letters Patent No. 92,626, dated July 13, 1869.

IMPROVEMENT IN PRISON-BARS.

The Schedule referred to in these Letters Patent and making part of the same.

To all whom it may concern:

Be it known that I, JEREMIAH A. MARDEN, of Boston, in the county of Suffolk, and State of Massachusetts, have invented a new and improved Prison-Bar; and I do hereby declare the following to be a full and correct description of the same, reference being had to the accompanying drawings, in which—

Figure 1 is an end elevation.

Figure 2 is a side elevation.

Figure 3 is a section.

In all the figures, the same letter indicates the same part.

A, in the accompanying drawings, shows the original bar, of common wrought-iron.

B shows an outer covering, of common cast-iron, chilled.

The nature of this invention consists in preparing the usual wrought-iron prison-bar with an outer surface or coating, that cannot be penetrated with a saw or other edged tool.

The chilled cast-iron surface or coating is super-added to the original wrought-iron bar by placing the original wrought-iron bar in an iron mould, leaving sufficient external space for receiving the molten metal which forms the chilled surface, in a manner well-known by iron-founders, and the two parts become firmly adhered together.

There is no secret in the process of thus uniting the two parts, and no unusual skill is required.

The material for the cast-iron chilled surface or coating is less expensive than the material used in the original wrought-iron bar.

Thus, the expense of preparing prison-bars in this manner is very slight.

It is evident, that when the chilled iron is super-added to the wrought-iron bar, the chilled coating may, at choice, be of any desired thickness, and that the wrought-iron bar may be of any desired diameter. But I prefer that the diameter of the wrought-iron bar be about three-fourths as great as is the entire diameter, after the chilled surface or coating has been applied, as it is the wrought-iron portion that is relied on for strength.

Having thus described my invention,

What I claim, and desire to secure by Letters Patent, is—

The iron prison-bar, constructed as described, and for the purpose set forth.

JEREMIAH A. MARDEN.
